UNITED STATES PATENT OFFICE.

RONALD F. McFEELY, DECEASED, LATE OF BEVERLY, MASSACHUSETTS, BY E. MARK SULLIVAN, ADMINISTRATOR, OF BOSTON, MASSACHUSETTS, ASSIGNOR TO UNITED SHOE MACHINERY CORPORATION, OF PATERSON, NEW JERSEY, A CORPORATION OF NEW JERSEY.

METHOD OF MAKING SHOES.

1,389,678.

Specification of Letters Patent. Patented Sept. 6, 1921.

Original application filed May 1, 1916, Serial No. 94,675. Divided and this application filed January 14, 1918. Serial No. 211,850.

To all whom it may concern:

Be it known that RONALD F. McFEELY, deceased, late of Beverly, in the county of Essex and State of Massachusetts, invented 5 certain Improvements in Methods of Making Shoes, of which the following description, in connection with the accompanying drawings, is a specification, like reference characters on the drawings indicating like 10 parts in the several figures.

This invention relates to methods of making shoes, the application being a division 15 of a prior application of R. F. McFeely, Serial No. 94,675, filed on May 1, 1916, upon which Letters Patent No. 1,366,472 were granted on Jan. 25, 1921. More particularly, the invention relates to methods of making 20 shoes which include in the toe portion of the upper a stiffening material, this material being usually provided for the purpose of insuring permanency in the shape of the toe of the shoe and of forming what is commonly known as a box toe. An object of the 25 invention is to provide an improved method for use in the manufacture of such shoes with a view to economizing time and expense in the manufacture of the shoes and also to avoiding possible injury to the shoe materials.

30 In shoes of the above mentioned character the stiffening material usually comprises a sheet of some substance which is comparatively stiff and hard at normal temperatures but is capable of being rendered pliable and adhesive by the application of heat, the stiffener blank sometimes being united to the other upper materials by the tip seam stitches or, alternately, inserted loosely between the upper leather and the lining immediately prior to the upper shaping operation. If the latter course is followed, it is customary to heat the stiffener blank to 35 soften it prior to its insertion in the shoe; and if the blank is stitched to the other materials, it is likewise softened prior to the upper shaping operation, usually by turning back the lining and applying heat directly to the stiffener. With the stiffener thus rendered soft and pliable, the upper materials, in one 40 well known method of manufacture, are

pulled over and fastened to the innersole in pulled over position at the end of the toe and at the sides of the ball of the shoe, after which the shoe is put aside for a subsequent lasting operation. The time elapsing between the pulling-over and the lasting operations permits the stiffener to harden, and makes it necessary to subject it again to the action of heat in order to 55 soften it before the lasting operation is performed. This method of procedure is objectionable, not only because of the time spent in resoftening the stiffener, which is increased by reason of the fact that the upper leather and the lining between which 60 the stiffener lies shield it to a large extent from the action of the heat, but also because it frequently happens that the application of heat to the shoe materials, notwithstanding the exercise of the greatest 65 care, works a permanent injury to the quality of the leather in the upper.

This invention, in one aspect, provides a method by which the necessity for resoftening the stiffener after the pulling-over 70 operation is entirely eliminated. In the manner herein illustrated of practising the method the upper materials are pulled over the last or equivalent shoe form while the toe stiffener is in a softened condition, 75 and before the stiffener has hardened in any material degree the upper is worked into permanently lasted shape around the toe. The inturned portion of the upper materials may be wiped down flat upon the margin of the innersole, as in a McKay shoe, or may be shaped to provide an upstanding flange along the rib of the innersole, as in a welt shoe. Where the stiffener is of such character as to require heat for 80 softening it, this method avoids the necessity for subjecting the upper materials to the action of heat with the consequent danger of injury to the upper leather.

85 In a further aspect the invention provides for utilizing the stiffening material in the toe portion of an upper which is shaped over a last or other shoe form to hold the upper in its acquired shape, thus eliminating the need of any extraneous fastening 90 95 100

around the toe prior to the stitching operation whereby the upper is secured to the innersole. To this end, it is contemplated that the pressure utilized in shaping the 5 marginal portion of the upper materials around the toe will be maintained until the stiffening material has set sufficiently to prevent any substantial reaction of the upper. In the use of some stock, when lasting over 10 an innersole, it may be preferable to fasten the upper to the innersole at the sides of the toe part, for example by driving one or more tacks through the margin of the upper and into the innersole at each side. Such tacks 15 may be driven in the vicinity of the tip seam, and when used serve to insure against displacement of the margin of the materials at the sides of the toe by the tension of the upper transversely of the last as well as to 20 assist in holding the materials against their tendency to pull backward over the end of the toe. It will be evident that on welt shoe work the portion of the stiffener which is shaped into an upstanding flange performs, 25 in large measure, after hardening, the function of the usual toe binder, and the tacks, when used, perform with respect to the hard stiffener flange a function similar to the function of the tacks commonly used to 30 anchor the ends of toe binders.

While it is contemplated that the novel method herein disclosed may be carried out in various ways, apparatus convenient for use in the practice of the method as applied 35 for example to the pulling-over and lasting of uppers is shown in the patent granted on the application of which this application is a division, and for the purpose of pointing out more fully one way in which the invention may be practised the accompanying 40 drawings show mechanism including portions of the machine illustrated in said patent.

In the drawings,

45 Figure 1 illustrates one way of softening the toe stiffener blank either before or after it is incorporated in the shoe.

Fig. 2 shows the upper of a welt shoe, including the heated and softened toe stiffener, 50 while held in pulled-over condition.

Fig. 3 illustrates the manner of lasting the toe portion of the shoe and of holding the upper materials in lasted position to permit the stiffener to harden.

55 Fig. 4 shows how the edge of the upper materials may be trimmed in the usual way while the materials are retained in lasted position by the hardened toe stiffener, and

60 Fig. 5 shows the toe portion of a welt shoe made in accordance with the method of this invention as it appears prior to the operation of stitching the upper to the inner-sole, this figure illustrating also the use of tacks at the sides of the toe part.

65 In Fig. 1 is shown a heating device 2 hav-

ing an interior chamber to which steam is admitted through a pipe 4 and provided with a plurality of openings 6 in its top through which the steam may escape. Upon the top of the device over the openings 6 70 may be placed a plurality of blanks *a* of stiffening material previously formed in the required shape to adapt them for use in the toe portion of shoes. These stiffener blanks need not differ in composition from blanks 75 such as have been commonly used heretofore in box toes, the composition being such as to render the stiffener hard and resilient at normal temperatures while permitting it to become pliable and adhesive when subjected to the action of heat. The stiffeners on the top of the heating device 2 are softened by the heat and are maintained in their softened condition ready for use. The heating device 2 in the construction shown is 80 also adapted for alternative use to soften a stiffener which has already been stitched in between the upper leather and the lining of the assembled upper materials of a shoe, the device having lateral openings each adapted 85 to receive the toe portion of a last together with the lining portion *b* of the shoe while permitting the upper leather *c* and the stiffener blank *a* to be positioned over the top of the device with the stiffener directly over 90 the openings 6. Devices of this character are well known, and have the advantage that the stiffener may be subjected to the required degree of heat without danger of damaging the upper.

When a shoe is to be pulled over, the operator may take one of the heated and softened blanks *a* from the heating device 2 and insert it in the usual way between the upper leather and the lining of the shoe, or if the work comprises upper materials in which the stiffener blank is permanently united to the other parts, the last and the assembled upper materials will be taken from the position with respect to the heating device in 100 which they are illustrated in Fig. 1. The work may then be presented to a pulling-over machine constructed, for example, as shown in the patent hereinbefore mentioned, where the upper materials, including the 105 softened toe stiffener, are seized by grippers 8 and pulled to stretch the materials transversely and longitudinally of the last. While the upper materials are held at the 110 end and the sides of the last in their tensioned condition and before the stiffener has had time to cool and harden in any material degree, the work is presented to lasting mechanism comprising toe embracing wipers 10 which assume control of the tensioned 115 upper and wipe the materials over the margin of the innersole on the bottom of the last. In the case of a welt shoe, as shown for example in the drawings, the wipers 120 increase the upper materials into the angle be-

between the feather and the rib of the inner-
sole and shape them into an upstanding
flange which extends along the rib around
the toe portion of the shoe. The wipers are
5 then held in operative position in engage-
ment with the upper along a continuous line
around the end and along the sides of the
toe while the stiffener is permitted to cool
and harden. The time which is required for
10 the stiffener to harden sufficiently to retain
the upper in lasted position will vary under
different conditions, but where the operator
is afforded facilities for pulling over an-
other shoe while a shoe previously pulled
15 over is in the lasting mechanism, as in the
construction shown in the patent above men-
tioned, the first shoe should be ready for re-
moval from the lasting mechanism by the
time when another shoe is ready for lasting.
20 When the upper materials are shaped to
provide an upstanding flange, as in the work
illustrated in the drawings, it will be evi-
dent that in the flange portion, where the
stiffener is exposed to the air, the stiffener
25 material will harden more quickly than at
other portions of the shoe. When the ma-
terial in this flange has attained a normal
degree of rigidity, the shoe may be safely
released from the lasting pressure of the
30 wipers, since the flange will serve as a binder
to retain the materials in lasted position.
If desired, moreover, either on work pro-
vided with such an upstanding flange, or on
other kinds of work, one or more tacks *d*
35 may be driven through the margin of the
upper and into the innersole, for example
in the vicinity of the tip seam, to assist in
holding the materials against transverse and
lengthwise strain. These tacks may be
40 driven by tackers 12 such as provided in the
machine shown in the patent, or they may
be driven by hand.

After the lasting operation has been com-
pleted and the stiffening material has cooled
45 and hardened, the edges of the upper may
be trimmed in a well known manner illus-
trated in Fig. 4, and the shoe may then be
presented to the sewing machine for secur-
ing the upper to the innersole. It will be evi-
50 dent that when a shoe is made by the method
herein described there is no binding wire
extending around the toe portion of the shoe,
or other extraneous fastening means such as
to interfere in any way with the sewing op-
55 eration, which is a further important ad-
vantage in the use of the method.

Although the novel method is described
herein with reference to portions of the ma-
chine shown in the patent granted on the
60 application of which this application is a
division as affording means convenient for
use in practising the method, it will be
readily understood that the method is not
dependent upon the use of any particular
65 machine or apparatus. Furthermore, it

should be understood that, except where re-
quired by the context, the invention is not
limited to a series of steps performed in the
precise order in which they are named in
the claims.

Having explained the nature of the inven-
tion and set forth fully how it may be practised,
what I claim as new and desire to
secure by Letters Patent of the United
States is:

1. That improvement in methods of mak-
ing shoes which consists in pulling over a
last both lengthwise and laterally the toe
portion of an upper including stiffening
material which is normally hard but has
80 been temporarily softened, after the upper
has been thus pulled at the end and the sides
of the toe and before said stiffening material
has had time to harden, working the pulled-
over upper into permanently lasted position
85 around the toe, maintaining the lasting pres-
sure until said stiffening material has sub-
stantially hardened, and then releasing the
upper from said pressure and utilizing the
stiffening material to hold the upper in
90 lasted shape.

2. That improvement in methods of mak-
ing shoes which consists in pulling over a
last and holding in tensioned condition at
the end and the sides of the last the toe por-
tion of an upper including material tempo-
rarily softened as by heat, then before said
stiffening material has had time to harden
wiping the margin of the upper over the
feather of the innersole and creasing it into
100 the angle between the feather and the rib of
the innersole to form an upstanding flange
around the toe, maintaining on a substan-
tially continuous line around the toe pres-
sure directed toward both the feather and
105 the rib of the innersole until the stiffening
material has substantially hardened, and
then releasing the upper from said pressure.

3. That improvement in methods of mak-
ing shoes which consists in pulling over a
last the toe portion of an upper including
stiffening material which is normally hard
but has been temporarily softened, working
the pulled-over upper into lasted position
110 around the toe while said stiffening material
is still soft, maintaining the lasting pressure
on the toe portion of the upper along a con-
tinuous line around the end and along the
sides of the toe until said material has har-
dened sufficiently to retain the lasted shape,
20 and then releasing the shoe from said pres-
sure and utilizing the stiffening material to
hold the upper in lasted position free from
any extraneous fastening around the end of
the toe.

4. That improvement in methods of mak-
ing shoes which consists in pulling over a last
the toe portion of an upper including stiff-
ening material which is normally hard but
has been temporarily softened, working the
130

pulled-over upper into lasted position around the toe before said stiffening material has had time to harden, fastening the upper to the innersole at the sides of the toe portion, 5 holding the upper in lasted position by the lasting pressure applied along a continuous line around the end of the toe until the stiffening material has hardened sufficiently to retain the lasted shape, and then releasing 10 the shoe from said pressure.

5. That improvement in methods of making shoes which consists in pulling over a last the toe portion of an upper including stiffening material rendered pliable and adhesive as by heat, molding the margin of the upper inwardly and shaping it to form an upstanding flange around the toe while said stiffening material retains the heat that rendered it pliable for the pulling-over operation, maintaining the molding pressure until the stiffening material has hardened sufficiently to retain the upper in lasted position around the toe and then releasing the upper from said pressure and utilizing the stiffening 25 material to hold the upper in lasted shape.

6. That improvement in methods of making shoes which consists in pulling over a last the toe portion of an upper including between the vamp and the lining stiffening 30 material rendered pliable and adhesive, working the margin of the upper into lasted position over the innersole and shaping it while the stiffening material is still pliable to form an upstanding flange extending 35 around the toe in a smaller curvature than the edge of the toe, holding the upper in lasted position by pressure applied on a continuous line around the toe until the stiffening material in said upstanding flange has set sufficiently to retain the upper materials in 40 lasted position around the toe, and then releasing the shoe and utilizing said flange as a binder to hold the upper in lasted position free from any extraneous fastening around 45 the end of the toe.

7. That improvement in methods of making shoes which consists in pulling over a last the toe portion of an upper including stiffening material rendered pliable and adhesive by heat, working the margin of the upper into lasted position over the innersole while the stiffening material is still pliable and shaping it to form an upstanding flange extending around the toe on the shoe bottom, 50 holding the upper in lasted position by pressure applied along a continuous line around the toe while permitting said stiffening material to cool and harden, tacking the upper to the innersole at the sides of the toe portion, 55 and then releasing the shoe from said pressure and utilizing the stiffening material to hold the upper in lasted position free from any extraneous fastening around the end of the toe.

65 8. That improvement in methods of making

shoes which consists in introducing between the toe portion of the vamp and the lining a sheet of toe stiffening material which has been rendered pliable and adhesive by heat and which is capable of becoming stiff when it cools, pulling over the shoe, then working the upper materials including said sheet of stiffening material into lasted position over the forepart of the last while the stiffening material still retains the heat 75 that rendered it pliable for the pulling-over operation and permitting said upper materials to cool and set while held under lasting pressure, and then releasing the shoe from said pressure and utilizing the stiffening 80 material to retain the upper in lasted position free from any extraneous fastening around the end of the toe.

9. That improvement in methods of making shoes which consists in shaping about a 85 form the toe end portion of an upper, including stiffening material rendered temporarily, pliable, and while said stiffening material is in a pliable condition working the marginal portion of the upper inwardly over 90 the form and shaping it to produce an upstanding flange around the toe adapted for attachment to the rib of an innersole, maintaining the shaping pressure on the upper while permitting said stiffening material to 95 set, and then releasing the upper from said pressure and utilizing the stiffening material to hold the upper in its acquired shape prior to attachment of said upstanding flange to the rib of an innersole. 100

10. That improvement in methods of making shoes which consists in shaping about a form the toe end portion of an upper, including stiffening material which is hard when cold and pliable and adhesive 105 when heated, and while said stiffening material is in a pliable and adhesive condition working the marginal portion of the upper inwardly over the form and shaping it to produce an upstanding flange around the toe adapted for attachment to the rib of an innersole, maintaining the shaping pressure on the marginal portion of the upper along 110 a substantially continuous line around the toe until the stiffening material in said flange has become substantially hard, and then releasing the upper from said pressure and utilizing said flange as a binder to assist in holding the upper in its acquired 115 shape free from any fastening around the end of the toe prior to attachment of said flange to the rib of an innersole. 120

11. That improvement in methods of making shoes which consists in shaping about a last the toe end portion of an upper including stiffening material rendered temporarily pliable, and while said stiffening material is in a pliable condition working the marginal portion of the upper inwardly over the feather of an innersole on the last 125 130

to form a flange upstanding against the rib of the innersole around the toe, maintaining the shaping pressure on the upper against the feather and the rib of the inner-
5 sole while permitting said stiffening mate-
rial to harden, and then releasing the upper
from said pressure and utilizing said flange
as a binder to assist in holding the upper

in lasted position free from any extraneous
fastening around the end of the toe.

In testimony whereof I have signed my
name to this specification. 10
